UNITED STATES PATENT OFFICE.

FRANK L. JAMISON, OF PITTSBURGH, PENNSYLVANIA.

INGOT-CASTING DEVICE.

1,336,234.

Specification of Letters Patent.

Patented Apr. 6, 1920.

Application filed July 21, 1919. Serial No. 312,191.

To all whom it may concern:

Be it known that I, FRANK L. JAMISON, a citizen of the United States, residing at Pittsburgh, in the county of Allegheny and 5 State of Pennsylvania, have invented certain new and useful Improvements in Ingot-Casting Devices, of which the following is a specification.

This invention relates to ingot-casting devices, and has for its object to provide a device of such class, in a manner as hereinafter set forth, with means whereby the cost of the casting of ingots is reduced and further to effectively prevent, when casting and 15 hardening, the formation of the defect known as "piping" due to the shrinkage of the metal during the setting and hardening thereof.

Further objects of the invention are to 20 provide an ingot-casting device for overcoming piping, which is simple in its construction and arrangement, strong, durable, efficient and convenient in its use, readily set up, and comparatively inexpensive.

With the foregoing and other objects in view the invention consists of the novel construction and arrangement of parts as hereinafter more specifically described and illustrated in the accompanying drawings, 30 wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a vertical sectional view of an ingot-casting device in accordance with this 40 invention, also showing a portion of an ingot.

Fig. 2 is a top plan view thereof.

Fig. 3, is a view similar to Fig. 2 with the hood removed.

Fig. 4 is a detail of the hood.

Referring to the drawings in detail an ingot-casting device in accordance with this invention comprises a mold formed of a body portion and a head, the former is indicated at 1 and the latter at 2. The mold is formed of two sections which are detachably connected in any suitable manner, or if desired the mold may be constructed of one piece. The mold may also be provided with

any suitable means so it can be transported 55 from point to point, by way of example a pair of trunnions or protuberances 2'.

The head 2, forms a continuation of the body 1, is of less length than the latter and is tapering in contour. The body 1 is rectangular in contour, although it is understood that it can be of any desired shape.

The walls of the body 1 are of greater thickness than the walls of the head 2, and the inner face of the walls of the latter form 65 a continuation of the walls of the body 1. A continuous ledge 3 is formed at the upper end of the body 1 and at the point of jointure of the head 2 with the body 1. The function of the ledge 3 will be presently referred to.

The ingot-casting device further includes a hood 4 which is adapted to be mounted on the head 2 to inclose the same and also to overlap the ledge 3. The hood 4 is rectangular in contour and comprises four depending walls 5, each having at its lower end an outwardly inclined scalloped extension 6, which when the hood 4 is mounted in position, overlap the ledge 3. See Fig. 1. The 75 scalloped extensions 6 provide air inlet openings 7. The hood 4 further includes a top 8, from which depend the walls 5, and said top 8, is formed with a central opening 8', which is closed by a removable shouldered plug 9, formed with a pair of vents 10. The top 8 is also formed with an opening 11 which not only acts as a vent but will also permit of one seeing the extent of metal 85 poured into the mold and also when the 90 metal is setting.

The plug 9, has pivotally connected to its upper face a valve 12, for opening and closing the vent openings 10. The valve 12, has a handle 13 so it can be conveniently shifted 95 when desired.

Arranged within the hood 4, at opposite corners thereof, are spacing members 14 which engage two corners of the head 2 for spacing the hood relatively to the head.

The shape of the hood 4 relatively to the shape of the head 2 provides a heating chamber 15, whereby the head 2 and the contents thereof and the upper portion of the ingot 16 within the mold may be heated to prevent 105 the premature solidification of the said upper portion of the ingot 16. The heat for the chamber 15 is derived from a series of

burners 17, mounted on the ledge 3, the latter forming a support for the said burners 17.

5 The burners 17 surround the lower end of the head 2 and are overlapped by the extensions 6. Leading to the burners 17 is a supply pipe 18 from a gas supply, which is provided with the valve 19 and air supply pipe 20.

10 The construction and operation of the ingot-casting device are such as to provide efficient means whereby the upper end of the ingot is maintained hot, so that when set the top thereof will not pipe but be formed 15 with a slight depression similar to that shown at 21.

What I claim is:

1. An ingot-casting device comprising a mold formed of a body portion and a head, 20 said head being of a different contour than the contour of said body and smaller than the latter, burners surrounding the lower portion of the head, a hood inclosing the head and overlapping the burners and provided with air inlets, said hood of a different contour from that of the head thereby forming a heating chamber surrounding the head, and said hood having its top provided 25 with vent openings.

30 2. An ingot-casting device comprising a

mold formed of a body portion and a head, 35 said head inset with respect to the top of said body thereby forming the latter with a ledge at its top, said head being tapering in contour, a hood mounted on the head and spaced from the sides of the latter to form a heating chamber, burners mounted on said ledge and overlapped by said hood, said hood having its top formed with vents, and means for opening and closing said vents. 40

3. An ingot-casting device comprising a mold formed of a body portion and a tapering head, a hood inclosing said head and having an opening in its top, a removable plug for closing said opening, said plug 45 having vent openings, means for opening and closing said vent openings, and burners supported by said body and surrounding the lower portion of the head and overlapped by the hood. 50

4. An ingot-casting device comprising a mold formed of a body and a tapering head, a hood inclosing and spaced from the head forming a heating chamber surrounding the head, burners surrounding the lower portion 55 of the head at the bottom of said chamber, said hood having an opening, and a vent plug mounted in said opening.

In testimony whereof I affix my signature.
FRANK L. JAMISON.
